INTERMITTENTLY ACTUATED MECHANISM

Thor H. Ljunggren, Charlestown, N. H., and Forrest A. Johnson, Springfield, Vt., assignors to Bryant Chucking Grinder Company, Springfield, Vt., a corporation of Vermont

Application October 25, 1945, Serial No. 624,452

6 Claims. (Cl. 192—138)

1

This invention relates to mechanism for intermittently moving a movable member by very small increments, as, for example, the movable member may be a feed carriage for feeding a tool and work relatively. Preferably the mechanism is of a type in which the frequency of actuation may be varied readily within wide limits and in which the extent of motion of the member moved at each actuation may be accurately very small.

A further object of the invention is to provide a ratchet mechanism by which very small and accurate step by step motions of the driven member may be made.

A further object of the invention is to arrange a limiting traveling element in such a way that it travels substantially slower than a shaft actuating a feed screw, making it possible to arrange the feed mechanism for a very fine incremental feed and at the same time allow for a large over-all range of the power feed movement.

Still another object of the invention is to provide a feed mechanism where the power feed is terminated at a predetermined position when a traveling element in the mechanism makes contact with a positive stop. This movable element is so arranged that further movement either in the feed direction or in a feed retracting direction can be made by hand without the element losing contact with the positive stop.

Still another object of the invention is to provide such a mechanism adapted to be actuated by a timing mechanism and independent of the position of the member being moved.

For a complete understanding of this invention, reference may be had to the accompanying drawings in which

Figures 1 and 2 are fragmentary front elevations and top plan views, respectively, of a grinding machine showing the mounting and actuation of the grinding wheel carriage.

Figure 3 is a sectional view on line 3—3 of Figure 2.

Figure 4 is an electrical diagram of an electronic actuating mechanism.

Figures 5 to 8, inclusive, are detail sectional views on the correspondingly numbered section lines of Figure 3.

Figure 9 is a detail sectional view on line 9—9 of Figure 5.

Figure 10 is a view similar to a portion of Figure 7, but with the latch element in inoperative angular position.

Referring first to Figures 1 to 3, at 1 is indicated the bed of a grinding machine on which is

10 supported a cross sliding carriage 2, this carriage as shown supporting a grinding wheel driving unit comprising a motor 3 driving a shaft 4, this shaft carrying the grinding wheel 5 on its end. The cross slide 2 is supported on a pair of spaced bars 6 extending across a casing 12 and the carriage 2 is operatively connected to a feed screw 7, by the rotation of which the slide or carriage 2 is moved back and forth on the slide bars 6.

15 For the purpose of this invention the feed screw 7 carries a worm wheel 8 (see Figure 3) with which meshes a worm 9 fixed to a feed shaft 10. The feed shaft 10 is journaled in bearings 11 and 11a in the casing 12 extending upwardly from the bed 1 and also extends into a housing 14 secured to the casing 12. Within the housing 14 the shaft 10 has keyed thereto the hub 15 of a ratchet wheel 16, and rockable on the bushing 15a on the hub 15 and between a pair of spacing washers 17, is a rock member 20. This rock member has pivoted thereto at 21 four arms 22 spaced around its axis and extending about and enclosing a ratchet wheel 16. As shown best in Figure 6, the ratchet wheel 16 has teeth, each of which has one steep face 24 and a less steep face 25, all the teeth facing in the same direction around the axis of the shaft 10. As shown there are twenty-five ratchet teeth. Cooperating with these 20 teeth are four spring-pressed ball detents 26 spaced equally around the periphery of the ratchet wheel and each housed within a socket 27 in the free end of one of the arms 22. Each is pressed toward the ratchet wheel as by a spring 28 bearing against the corresponding arm 22 and within a socket 29 of the rock member 20 and backed up by a threaded closure plug 30.

25 It will be noted that with the four detents and twenty-five ratchet teeth, the detents are spaced 30 incommensurate with the teeth so that only one detent is in position at one time to engage fully between adjacent teeth of the ratchet wheel. Thus as shown the left hand detent 26 is so engaged while each of the others is more or less retracted. The detent in engagement is then in driving relation to a steep face 24 on the ratchet wheel 16 so that when the rock member 20 is rocked clockwise it will turn the ratchet wheel 16. Each of the detents is wedged back against 35 a spring on the reverse rocking motion of the rock member 20 by virtue of lesser steepness of face 25 so that the ratchet wheel 16 does not turn at the reverse motion of the rock member 20. With this arrangement a very precise extent of 40 motion forwardly of the ratchet wheel is produced

by each rocking action so that the extent of each angular motion of the feed shaft 10 is accurately controlled in accordance with the extent of rocking of the rock member. In the arrangement shown an amplitude of rocking oscillation of the member 20 sufficient only to bring the several detents successively into operative relation will produce one hundredth of a revolution of the shaft 10 at each complete double oscillation. The rock member 20, as shown best in Figure 9, is provided with a pin 300 projecting therefrom which extends into a slot 31 of a reciprocating member 32 by the reciprocation of which the rock member is given its rocking motions in opposite directions.

As shown in Figure 5, the member 32 comprises a rod which extends slidably through a bushing 33 through a wall of the housing 14. Its lower end is connected to the slidable core 35 of an electromagnet 36. Its upper end extends into a tubular casing 37 and its threaded into a bushing 38 within this casing, the bushing bearing against a coil spring 39 surrounding the bar 32 and reacting between the bushing and a base 40 of the casing 37 through which the bar 32 passes. The casing 37 is shown as threaded into the upper end of the housing 14. The bushing 38 has a head 42 by which it may be turned to adjust the pressure exerted by the spring 39 and its normally covered by a cap 43 which may be secured to the upper end of the bar 32 as by a set screw 44. It will be evident that by alternately energizing and de-energizing the solenoid 36, the rock member 20 may be rocked back and forth, the pull of the solenoid rocking it in one direction and the pull of the spring 39 returning it, and the adjustment of the sleeve 37 in the casing will serve to determine the point from which the start of the rocking motion begins.

Means are provided by which the total normal extent of power feed may be limited and in accordance with which nearly four full turns of the shaft 10 may be had. To this end the shaft 10 has keyed thereto a pinion 50 within the housing 14, and this pinion meshes with three planetary pinions 51, each journaled on a pin 52 and 52a projecting from a spider 53 journaled on a bushing 54 surrounding shaft 10. The planetary pinions 51 also mesh with an internal gear ring 56 positioned between a pair of friction disks 57 and 58. The disk 57 bears against a shoulder 59 on the inner wall of the casing 14, and the disk 58 is pressed against the gear ring by a pair of Belleville washers 55 engaged by the inner end of a head 60 threaded into the outer end of the casing 14. One of the pivots of the planetary pinions 51, as 52a, projects through the spider and may impinge upon a stop rod 65 slidably mounted within a guide tube 66 projecting within the casing 14, the outer end of this rod 65 when pressed to the left, as viewed in Figures 7 and 10, actuating a stop switch 68. This switch is normally closed and after rod 65 has been pushed the switch will open and stay in this position until reset button 65a is pushed, when the switch returns to its normally closed position. Before contacting the stop rod 65, the pin 52a engages and lifts a latch element 70 pivoted at 71 between a pair of jaws 72 of a rock shaft 73. This latch element 70 is mounted on one side of the axis of the rock shaft 73 so that when this axis is turned from the position shown in Figure 7 into that shown in Figure 10 in clockwise direction viewed from its outer end through 90°, its end is raised above the pin 52a so that the pin 52a may be retracted as will

later appear. In the position shown in Figure 7, it acts by gravity to prevent retraction of the element 52a from the stop rod 65 when it has once reached stopping position. A pin 74 projecting from the casing 14 into a segmental cutout 75 of a knurled actuating knob 76 secured to the outer end of the rock shaft 73 defines the rocking limits of the rock shaft.

Reverse rotation of the shaft 10 may be accomplished at any time by grasping and turning a hand knob 80 secured to the outer end of the shaft 10, the detents 26 being pressed back when such turning is effected. The knob 80 is shown as threaded onto the outer end of a cylindrical block 81 through which the shaft 10 passes and to which it is secured as by a nut 82 threaded on its outer end and lying within a recess 83 in the outer end of the block 81. The block 81 is keyed to the shaft 10. A plurality of outwardly spring pressed balls 84 riding in radial sockets 85 within the block 81 engage a V internal groove 86 in a sleeve 87 and frictionally hold the sleeve 87 to turn with a knob 80. This sleeve 87 may be provided with peripheral graduations thereon cooperating with a stationary index finger 88, so that after the sleeve has been set in the desired angular relation to the block 81, the extent of its rotation may be indicated by change in the indicator marks coming opposite to the pointer 88.

The mechanism may also be given a hand controlled feed motion, after the stop has acted to prevent further power feed. This is done by turning the knob 80 in feed direction, this acting through the engagement of the pinions 51 thereon to turn the internal gear 56 between its friction holding disks 57 and 58, the member 53 with its pinion pivots 52 and 52a being held stationary by reason of the engagement of the pivot 52a against the stop rod 65 and its stationary surrounding guide tube 66. During this action the detents engaging the ratchet wheel 16 are wedged back successively by the faces of the ratchet teeth which engage them.

The ratchet mechanism hereinbefore described is adapted to be actuated, without reference to or control by the member being moved, by a timing mechanism which alternately energizes and de-energizes the solenoid 36. While such timing mechanism is per se not a part of our invention, for the purpose of illustration an electronic timing mechanism particularly suited for this purpose is illustrated in Figure 4. Two triode tubes with indirectly heated cathodes are shown at T1 and T2. Governing the grid circuits of these tubes are separate potentiometers P1 and P2. The tube anode circuits control the relays R1 and R2. Relay R1 has a double throw switch element 100 with contacts a and b. Relay R2 has a single throw switch element 101 with the contact c. Current is taken from a suitable source of supply through leads 102 and 103 and a main switch 104 to the primary of a transformer 105. The secondary 106 of the transformer supplies energy to the relays R1 and R2 and a separate secondary winding 107 supplies heating current to the cathodes of the tubes T1 and T2. Contact a connects through the lead 108 with one side of the solenoid 36, the other side leading back through lead 109 and the knock-off switch 68 and lead 110 to the line 102 inwardly of the main switch 104.

Assuming the switch 104 to be closed and with the relay contacts as shown, the contact c being closed, places the grid G1 of the tube T1 at

zero potential. Therefore the tube T₁ is conducting and the relay R₁ will become energized and close the contact at b, opening the contact at a. Contact b when closed removes negative potential from the delay network of the tube T₂, this delay network including the potentiometer P₂ and the condenser 111, allowing the charge of this condenser to leak off through the potentiometer P₂ until the negative voltage at the grid G₂ of tube T₂ no longer controls anode current and relay R₂ becomes de-energized. This allows the grid condenser 112 of the tube T₁ to build up its negative charge so that the anode of T₁ no longer conducts and relay R₁ becomes de-energized, closing the contact a which operates the solenoid 36. As the relay R₂ is opened, contact c closes, removing the negative potential of the delay network of the tube T₁ so that after the delay relay R₁ is energized, again closing the contact at b and opening that at a. This removes the negative potential from the delay network of the tube T₂ after negative potential leaks from the condenser 111. The anode then passes current and the relay R₂ operates as before. The potentiometer P₂ is as a rule adjusted once and for all through a time delay suited to give the solenoid core ample time after the energization of the solenoid 36 to travel the whole length of its path and set against the pole piece. This potentiometer can then be located on the tube and relay panel in the control cabinet of the machine as it is only adjusted at rare intervals. The potentiometer P₂ is intended to govern the energizing frequency of the solenoid by way of impressing on the grid an impulse of variable intensity which is dependent upon the setting of the potentiometer P₂. The control of this potentiometer should therefore be at a point easily accessible to the operator and is shown on Figure 1 as on the forward face of the machine.

One of the several methods by which this feed mechanism can be utilized is as follows. The grinding wheel is brought in contact with the work piece and the power feed is started. Grinding is now automatic as the grinding wheel is reciprocating past and in contact with the work piece and the power actuated feed moves the wheel at predetermined time intervals by small increments against the work until the travelling element 52a on the spider for the planetary gearing hits the stop 65 at the predetermined amount of travel. This arrests further movement of the power feed by operating the switch 68. This is apparent to the operator from the fact that the cap 43 ceases its up and down movement. The wheel may be backed off at once, or it can be allowed to "dwell" during a "spark out" period. In either case the dial 87 is set on zero at pointer 88. The tool and work piece are separated, this completing the rough grinding operation. The work piece has now been cleaned up and on it has been generated a surface with a reasonably high degree of finish as to circular form, straightness, and dimension, leaving just enough stock to be removed in a later finishing operation intended to impart a specified fine dimensional tolerance and surface finish. When wheel and work are separated, a truing device, commonly a diamond point, is placed in the path of the wheel to true it and make it keen and accurate for the finish grinding. Any amount dressed off the wheel is compensated for by turning the hand wheel 80 the desired

amount and thereafter resetting the dial 87 to zero.

The wheel is then returned to the work for the finishing operation, during which the hand wheel is moved in feeding direction by the amount required to produce the final work sizes desired. After finish operation the driving element 52a is released by operating the latch 70 and this element 52a can now, by means of the hand wheel 80, be returned to its initial position.

From the foregoing description of an embodiment of this invention, it should be evident to those skilled in the art that various changes and modifications might be made without departing from the spirit or scope of this invention.

We claim:

1. In combination with a rotary feed shaft, an internal gear concentric with said shaft, friction means normally holding said internal gear stationary, a gear fixed to said shaft in the plane of said internal gear, a planetary gear between and meshing with said internal gear and said fixed gear, a spider to which said planetary gear is journaled, power means for turning said shaft, an element carried by said spider, a stop for said turning means located in the path of motion of said element to be actuated by impingement thereon of said element at a predetermined angular position of said element, and manually operated means for turning said shaft in normal feed direction while said element is stationary, the turning of said shaft then turning said internal gear against the action of said friction means by the rotation of said planetary gear.

2. In combination with a rotary feed shaft, an internal gear concentric with said shaft, friction means normally holding said internal gear stationary, a gear fixed to said shaft in the plane of said internal gear, a planetary gear between and meshing with said internal gear and said fixed gear, a spider to which said planetary gear is journaled, power means for turning said shaft, an element carried by said spider, a stop for said turning means located in the path of motion of said element to be actuated by impingement thereon of said element at a predetermined angular position of said element, manually operated means for turning said shaft in normal feed direction while said element is stationary, the turning of said shaft then turning said internal gear against the action of said friction means by the rotation of said planetary gear, latch means engageable with said element and normally preventing said element from being retracted from said predetermined position, and means for releasing said latch means to permit said shaft to be turned in reverse direction while said internal gear is stationary.

3. In combination with a rotary feed shaft, power means for turning said feed shaft step by step, means for stopping said power feed at a predetermined feed position of said shaft, said means including a spider rotatable on said shaft, reduction gearing from said shaft to said spider, an element carried by said spider, and means engageable by said element at a predetermined angular position of said spider for stopping rotation of said spider in either direction.

4. In combination with a rotary feed shaft, power means for turning said feed shaft step by step, means for stopping said power feed at a predetermined feed position of said shaft, said means including a spider rotatable on said shaft, reduction gearing from said shaft to said spider,

an element carried by said spider, means engageable by said element at a predetermined angular position of said spider for stopping rotation of said spider in either direction, said gearing including a friction connection, a yieldable connection interposed between said power means and said shaft, and an operator-actuable means for turning said shaft, said friction and yieldable connections permitting said shaft to be turned in either direction at any time by said operator-actuable means regardless of said power means and said stopping means.

5. In combination with a rotary feed shaft, a normally stationary internal gear concentric with said shaft, a gear fixed to said shaft in the plane of said internal gear, a planetary gear between and meshing with said internal gear and said shaft-carried gear, a spider to which said planetary gear is journaled, an element carried by said spider, means for turning said shaft, a stop for said turning means located in the path of motion of said element to be actuated by impingement thereon of said element at a predetermined position of said element, and means actuatable to rotate said planetary gear and said internal gear while said turning means is stationary.

6. In combination with a rotary feed shaft, an internal gear concentric with said shaft, friction means normally holding said internal gear stationary, a gear fixed to said shaft in the plane of said internal gear, a planetary gear between and meshing with said internal gear and said fixed gear, a spider to which said planetary gear is journaled, power means for turning said shaft, an element carried by said spider, a stop for said turning means located in the path of motion of

5 said element to be actuated by impingement thereon of said element at a predetermined angular position of said element, and manually operated means for turning said shaft in either direction while said element is stationary, the turning of said shaft then turning said internal gear against the action of said friction means by the rotation of said planetary gear.
